To all whom it may concern:

Be it known that I, ADOLPH PETZOLD, a citizen of the United States, residing at the city of Philadelphia, State of Pennsylvania, have 5 invented and produced a certain new and original Design for Rugs, of which the following is a full, clear, and exact description, reference being had to the accompanying drawing, forming a part of this specification.

10 My design is applicable to and intended for the surface ornamentation of woven rugs.

In its essentials it consists, as shown in the drawing, of a rectangular border composed of a connected series of curved line or scroll 15 figures *a*. Proceeding from the longer side of the border figure at each end of the field cen-

ter is a scroll figure *b*, so arranged as to leave outside spaces filled by small floral figures *c* at each of the four corners and an inside central space or field in which is an ornamental figure *d*, composed of a bunch of flowers surrounded by large leaves. 20

I claim—

The design for a rug; substantially as shown and described. 25

In testimony whereof I have hereunto affixed my signature this 24th day of May, A. D. 1901.
